COMBINED KEY CHAIN AND WATCH

Vincent A. Parell, Miami, Fla.

Application December 12, 1949, Serial No. 6,564

Term of patent 14 years

(Cl. D42—8)

To all whom it may concern:

Be it known that I, Vincent A. Parell, a citizen of the United States, residing at Miami, Florida, have invented a new, original, and ornamental Design for a Combined Key Chain and Watch of which the following is a specification, reference being had to the accompanying drawing, forming a part hereof.

Fig. 1 is a front view of a combined key chain and watch, showing the essential features of my new design in full lines, the key chain shown in broken lines being omitted from Figs. 2 and 3 for convenience of illustration.

Fig. 2 is a side elevational view, and

Fig. 3 is a back view of the same.

I claim:

The ornamental design for a combined key chain and watch as shown and described.

VINCENT A. PARELL.
